CLAIM

The ornamental design for a rifle monopod as shown and described.

DESCRIPTION

1. Rifle monopod
- 1.1 : Side view;
- 1.2 : Rear view;
- 1.3 : Side view;
- 1.4 : Front view;
- 1.5 : Bottom view;
- 1.6 : Top view;
- 1.7 : Perspective view;
- 1.8 : Perspective view;
- 1.9 : Perspective view;
- 1.10 : Perspective view;
- 1.11 : Perspective view;
- 1.12 : Perspective view;

The design is a rifle accessory for precision shooting and hunting to allow the rifle to stand at a steady elevation when used; the article is used to maintain the current sight elevation; it has a micrometric adjustment by a wheel on its frame.
